DESIGN FOR A PLANT STAND

Neal W. Houlahen, Etna, Pa.

Application August 31, 1940, Serial No. 94,756

Term of patent 7 years

To all whom it may concern:

Be it known that I, Neal W. Houlahen, a citizen of the United States, residing in Etna, in the county of Allegheny and State of Pennsylvania, have invented a new, original, and ornamental Design for a Plant Stand, of which the following is a specification, reference being had to the accompanying drawing, forming a part thereof.

In the drawing Fig. 1 is a plan view of a plant stand showing my new design; and Fig. 2 is a front elevation thereof.

I claim:

The ornamental design for a plant stand, substantially as shown.

NEAL W. HOULAHEN.
